UNITED STATES PATENT OFFICE.

LORENZ KONRAD BRAREN, OF MUNICH, GERMANY, ASSIGNOR TO THE FIRM FRIEDRICH DECKEL, FABRIK FÜR PRÄZISIONSMECHANIK UND MASCHINENBAU, OF MUNICH, GERMANY.

LUBRICATION FOR SCREW MAKING AND TURNING LATHES.

Application filed June 9, 1924, Serial No. 718,724, and in Germany July 2, 1923.

The object of my invention is to provide an improved type of lubrication for the cutting tools used in an automatic screw machine, whereby the lubricant or coolant is 5 delivered direct to the different cutting points without employing the usual line of piping that hampers more or less the operation and adjustment of the cutting tools.

A further object of my invention is to provide 10 means for effectually preventing any splashing and throwing off of the lubricant from rotating cutting tools.

The lubricant under the improved system is caused to flow axially in the feeding direction of the material completely surrounding the latter, impinging thus against any tool coming into contact with the material. In this manner a very perfect lubricating and cooling action is achieved whereby also 20 all chips are washed away right after having formed. This manner of lubrication is especially of advantage for tools working axially and surrounding the end of the material as for instance hollow mills and threading dies where otherwise a perfect lubrication is doubtful.

Of course although my invention is shown applied to turning and threading lathes it may as well be used for any similar machine 30 tool where a bar of material is held by a collet, chuck or other gripping device and where one or more tools are performing cutting operations near to the holding point.

In the drawings accompanying and forming part of this specification Fig. 1 is a side elevation of an automatic screw machine with the invention applied. Fig. 2 is a view of the spindle nose partly in section on an enlarged scale. The stand 1 for the frame 2 of the screw machine is formed in the upper part to serve as a container 3 for the lubricant or coolant. A pump 4 in the present case a gear pump driven by a pulley 5, delivers lubricant under pressure into the 40 pipe line 6, a by pass 7 permitting the liquid to stream back into the container 3 when the pressure in the line 6 exceeds a certain amount. The pipe line 6 is arranged inside of the container 3 up to a point 8 in the 45 cover plate 10 underneath a bore 9 in the frame 2 so that a straight connection with union 11 and regulating cock 12 is all that may be seen of the lubricant system from

the outside. A spindle 13 is journaled in a bore of the frame 2. The bar of material 14 is located inside of the spindle and held there in well known manner by a collet 15 and is passed forward by a feeding mechanism which is also of well known construction. Surrounding the nose of the spindle 60 13 there is a cap 17 held in a bayonet manner by two shoulder screws 18 against the face of the frame 2.

The rear portion of the cap 17 is a running fit over an enlarged portion of the spindle 13 while the front part surrounds the nose of the spindle with a certain amount of clearance. A hole 19 connects this space with the bore 9 in the frame 2 permitting the lubricant to enter. A conical hole in 70 the front wall of the cap 17 for the bar of material 14 to pass through is made large enough to permit a tubular stream of liquid to flow through enveloping completely the bar of material.

A groove 20 in the rear portion of the cap 17 with a hole 21 connecting to the outside is provided for draining off any liquid forced through the running fit towards the rear and preventing it entering the bearing 80 of the spindle.

A tool carrier 16 pivoted to the frame 2 with a tool 22 fastened to it shows how the lubrication of a stationary tool is accomplished.

A threading die 23 on a holder 24, which is fastened to a spindle 25 is used for cutting threads on the end of the part worked upon. To prevent the lubricant being thrown off by the fast rotating die a tubular guard 26 90 has been provided which is fastened to a collar 27. The latter is held axially between the die holder 24 and a collar 28 but is free to turn on the spindle 25. Two pins 29 opposite each other on the collar 27 prevent rotation and are adapted to slide in grooves 30 of a tube 31 which is fastened by screws 32 to the bearing 33 of the thread mechanism housing 34. The latter is mounted on the frame 2 of the screw machine. The lubricant returns through a filter 35 100 to the oil reservoir 3.

Having now fully explained the nature of this my invention I do not wish to be understood as limiting myself to the exact details 105 of construction nor to the particular appli-

cations shown, as obviously many modifications will occur to a person skilled in the art.

What I claim is:

5. 1. In a lubricating system, a holder for a work piece, a casing surrounding the holder including an end wall having an opening slightly larger than the work piece through which the latter is adapted to project, a 10 lubricant supply source, and a pump adapted to force the lubricant to said casing and axially therefrom through said opening in a relatively thin stream upon that portion of the work piece projecting from the casing.
15. 2. In a lubricating system, a holder for a work piece, a casing forming a chamber around said holder and having a relatively small discharge passage in its end wall through which the work piece is adapted to 20 project and around which a relatively thin stream of lubricant is adapted to be discharged coaxially of the work piece and upon the projecting portion thereof, and means for supplying lubricant to the chamber.
25. 3. In a turning and threading machine, a work holder adapted to support a work piece, a casing for the holder forming a lubricant chamber about the same, said casing including an end wall through which a portion of the holder is adapted to project in slightly spaced relation whereby to form a restricted discharge passage for the lubricant coaxially of the holder to effect discharge of the lubricant upon the work piece projecting from the holder, and means for supplying lubricant to the chamber.
40. 4. In a turning and threading machine, a work holder, a casing for the holder forming a lubricant chamber about the same, said casing including an end wall through which a portion of the holder is adapted to project in slightly spaced relation whereby to form a restricted discharge passage for the lubricant coaxially of the holder, a cutting tool 45 for the work rotatable about the axis of the holder, a sleeve encircling the cutting tool adapted to receive the lubricant thrown off thereby, and means for supplying lubricant to said chamber.
50. 5. In a turning and threading machine a lubricant pump, a pressure line, a chamber connected to said pressure line, a holder for the bar of material worked upon extending 55 into said chamber and an orifice surround-

ing the bar of material to have the liquid flow axially surrounding the material from said chamber.

6. In a turning and threading machine a 60 rotating holder for gripping the bar of material worked upon, a bearing for said holder, a chamber partly surrounding said holder for receiving the lubricant under pressure, an orifice in said chamber for causing the liquid to flow onto and in the axial 65 direction of the bar of material and means for preventing liquid from passing from the chamber to the inside of said bearing supporting the material holder.

7. In a turning and threading machine a 70 holder for gripping the bar of material worked upon, a rotating tool working axially upon the end of material protruding from said holder, a pressure line for the lubricant, 75 means for causing the liquid to flow onto and in the axial direction of the bar of material against said rotating tool working axially upon the material and means for preventing the liquid from flying off from the rotating tool.

8. In a turning and threading machine, a 80 holder for gripping the bar of material worked upon, a rotating tool working axially upon the end of material protruding from said holder, a pressure line for the lubricant, 85 said pressure line leading the lubricant close to said holder, an orifice for causing the stream of lubricant to flow substantially in the axial direction of the material against said rotating tool, and a guard surrounding said rotating tool for catching any liquid thrown off thereby, said guard being arranged to move axially with said rotating tool but being held against rotation.

9. In a turning and threading mechanism 90 means for holding the bar of material worked upon, a rotating tool working upon the end of said bar of material and protruding from said holding means, said rotating tool also performing axial movements, 100 a lubricating line discharging lubricant onto the bar of material and the rotating tool, a guard for catching the liquid thrown off by the rotating tool and means for causing said guard to move axially with said rotating tool but adapted to prevent rotation of the guard.

In testimony whereof I affix my signature.

LORENZ KONRAD BRAREN.
